MULTICHANNEL SYSTEM

Emile Labin, New York, N. Y., assignor to Federal Telephone and Radio Corporation, New York, N. Y., a corporation of Delaware

Application August 25, 1944, Serial No. 551,202

15 Claims. (Cl. 179—15)

1 This invention relates to multi-channel communicating system and more particularly to systems for transmitting in interleaved manner the time modulated pulses of a plurality of channels.

One of the objects of the invention is to provide a multi-channel transmitter and method for either multi-channel transmission to a second terminal or for multi-channel broadcasting from a given station for selective reception by individual receivers.

Another object of the invention is to provide a new method and means for time modulating a train of pulses.

In most multi-channel communicating systems employing pulse time modulation, each channel is provided with an individual time modulator. According to one of the features of my invention I provide a single time modulator for all of the channels. A pulse train corresponding to the interleaved pulses of all the channels is applied to the modulator and the signal energy of each channel is divided into spaced pulse segments timed differently for the different channels, the pulse segments of the signal energy of all the channels being applied in interleaved manner to the time modulator as the modulating energy. The pulses of the train are displaced in time in accordance with the amplitude of the corresponding pulse segments. This method of modulation may of course be employed for a single channel where desired, one of the advantages of such a system for a single channel, or even for multi-channel transmission, being that the interval between pulse segments of any one channel may be blocked at the receiver thereby insuring a high signal-to-noise ratio. Another advantage of the system particularly in multi-channel operation is a reduction in the number of time modulators required by such systems heretofore proposed.

For a further understanding of the invention, reference will be had to the following detailed description to be read in connection with the accompanying drawings, in which:

Fig. 1 is a block diagram of a multi-channel transmitter in accordance with the principles of this invention;

Fig. 2 is a graphical illustration useful in explaining the operation of the transmitter of Fig. 1;

Fig. 3 is a schematic wiring diagram of a pulse time modulator that may be used in the system of Fig. 1;

Fig. 4 is a block diagram of a further embodiment of the invention, and

Fig. 5 is a graphical illustration used in ex-

plaining the operation of the embodiments shown in Fig. 4.

The multi-channel transmitter shown in Fig. 1 may comprise the transmitting equipment for a two-way multi-channel communicating system or it may be used as a multi-channel broadcasting system for selective reception of the channels by individual receivers. In the case of multi-channel broadcasting the transmitter, of course, will be provided with a suitable omni-directional antenna. For simplicity of illustration the system is shown for three transmitting channels, 1, 2 and 3, although many additional channels may be included, if desired.

15 The embodiment shown in Fig. 1 includes a stable type of pulse producer 4 of known form for producing a train of pulses such as indicated at 5 in graph a of Fig. 2. The repetition rate of the pulses 5 is selected in this embodiment as that 20 pulse rate desired for a single channel. The pulses 5 are multiplied according to the number of channels desired by applying the pulses to a pulse multiplier 6 of known character which may or may not include a pulse shaper. Preferably 25 the output pulses 7 of multiplier 6 are narrow pulses as indicated by graph c.

30 Energy of the pulses 5 is also applied to a pulse shaper 8 to produce pulses of a desired width as indicated at 9 in graph b. The pulses 9 are used for two purposes, one for selecting spaced portions of the signal energy of each channel, and the other for synchronizing receivers.

35 The synchronizing pulses may be differently shaped, if desired by applying pulses 5 to pulse shaper 8a through connection 8b. In the present showing, however, the same pulse width is used for synchronizing purposes and for selecting segments of signal energy. The output pulses 9 of shaper 8 are applied to a delay network 10 having 40 output connections 11 spaced at different retardation points therealong whereby pulse energy may be supplied at different time intervals corresponding to the timing desired for pulses of the different channels. The output connection for channel 45 1 is applied to an amplifier 12 which is normally blocked. The signal source 13 for channel 1 is also applied to the amplifier 12 but the blocking potential for the amplifier is so chosen that the signal energy remains blocked regardless of its 50 variations in amplitude. The retarded or keying pulses from output connection 11a unblock the amplifier for the duration of each of the pulses. This passes a segment of the signal energy, or rather produces in effect an output pulse which 55 is amplitude modulated in accordance with the

segment of signal energy coincident with each keying pulse.

In graph *b*, for example, the pulses 14, 15 and 16 represent three successive output pulses from amplifier 12 which are representative segments of the signal envelope 17. These signal pulses thus define points along the signal envelope 17 as indicated.

The output pulses of each of the amplifiers of the different channels are applied over connection 18 to a time modulator 19 to which is also applied the pulses 7, graph *c*. The signal pulses of the different channels are interleaved in accordance with the retardation applied thereto in delay device 10. Pulses 14, 15 and 16 are shown to be retarded an amount t_1 causing them to coincide with the pulses of channel 1. For channel 2 the pulses 9 are retarded an amount t_2 for coincidence with pulses of channel 2. It will be clear, therefore, that the amplitude modulated pulses of each channel coincide in time with pulses of the pulse train 7 of graph *c*.

The time modulator 19 may be of any desired character capable of displacing in time the pulses 7 in accordance with the amplitude of the corresponding pulses applied over connection 18. Two examples of time modulators of this character are hereinafter described in connection with Figs. 3 and 4.

Graph *e* of Fig. 2 illustrates the time displacement produced on the pulses of channel 1 by the pulses 14, 15 and 16 of graph *d*. The low or minimum amplitude of pulse 14, which may be regarded as corresponding to the maximum negative signal value, is indicated as having retarded pulse 1a of channel 1 an amount T . This minimum amount of retardation for pulse 14 may be regarded as always present in the time modulator. The amplitudes of pulses 15 and 16 are shown to time displace the pulses 1b and 1c amounts $T+\Delta t$ and $T+2\Delta t$ respectively, since they are of successively greater signal values. It will be clear that the time displacements of the pulses of the several channels vary in amounts according to the instantaneous values of the corresponding signal energies, and that the displacements are relative to the pulse positions of train 7 in the absence of modulation or with respect to the positions of the pulses *S* of the synchronizing channel (graphs *f* and *g*).

The pulse energy 9 from shaper 8 is applied over connection 20 to a clipper mixer 21 to which is also applied the time modulated pulse output of modulator 19. The synchronizing pulses being the same as pulses 9 in graph *b* as to width and timing coincide with pulses of a fourth channel in the train of pulses 7. By providing the mixer 21 with a limit clipping level indicated at 22 in graph *f* the pulses 4 are replaced by synchronizing pulses *S*, the resulting train of pulses for transmission being as shown by graph *g*. These pulses are applied to transmitter 23 for transmission at a given carrier frequency over antenna 24 which may be of a directional or omni-directional type.

Referring to Fig. 3 a pulse time modulator is shown that may be employed as the time modulator 19 in Fig. 1. The time modulator comprises a retardation circuit 25 having an inductance coil 26 with a core of iron or other permeable material, and condensers 27, 28.

The minimum retardation characteristic of the circuit 25 may be represented by the time interval T of graph *e*, Fig. 2 for a maximum negative signal value such as indicated by pulse 14. The

signal pulses of graph *d* which vary in amplitude in accordance with segments of the signal energy are applied over connection 19 to the anode circuit 29 of an amplifier 30 to which is applied over connection 31 the pulses 7 from pulse multiplier 6. The source of anode voltage is applied through the resistor 32 and the retardation circuit 25. Should the impedance of coil 26 be sufficient the resistor 32 may be omitted.

The instantaneous signal value of the signal envelope 17 at the occurrence of pulse 15 is greater than the minimum value at the occurrence of pulse 14, and therefore produces greater retardation effect on pulse 1b by a total amount equal to $T+\Delta t$. This greater retardation of the pulses 1b over pulses 1a is produced by a change in permeability of the core of coil 26, which alters the inductance of the circuit 25. The still greater signal value represented by pulse 16 produces a still greater retardation for pulses 1c which equal to $T+2\Delta t$. From the foregoing it is believed clear that as the signal energy increases still further, the greater the time displacement will be for the corresponding pulses of channel 1. The time displacement according to this method of modulation is of course small but small displacements are of advantage in multi-channel communication since a larger number of pulses is possible for a given time interval. For a further discussion of this principle of time modulation reference may be had to my copending application Serial No. 546,378 filed July 24, 1944.

In Fig. 4 I show an embodiment of the invention wherein pulse producer 33 is arranged to produce pulses at the repetition frequency desired for all of the channels taken together. The pulse output of producer 33 is represented by the pulse train 34 in graph *m* of Fig. 5. To obtain the pulses for each channel, the pulse train 34 is applied to a pulse divider 35 whereby pulses 36, graph *n* are produced. These pulses are then applied through a pulse shaper 37 to a delay network 38 similar to the device 10 in Fig. 1. The pulse energy 36 is thus shaped and delayed for channel 1 as indicated by the pulses 39, 40 and 41 of graph *o*. These wider delayed pulses are applied to channel amplifier 42 for selecting a segment of signal energy from source 43 in the manner hereinbefore described. The output pulses 39, 40, 41 of amplifier 42 are thereafter applied to a clipper gate 44, for translation of the amplitude modulation thereof into time modulation.

If a time modulator of the character shown in Fig. 3 were employed in the system of Fig. 4, the pulses 34 would be applied directly thereto as hereinbefore described in connection with Fig. 1. Before application of pulse energy 34 to clipper gate 44, it is desirable to reshape the pulses into pulses each having at least one inclined edge corresponding in time to one of the pulses of the several channels. The energy of the pulse train 34 is therefore applied to a wave producer 45 of the type capable of producing a zig-zag shaped wave 46, the undulations of which are shown in graph *p*, symmetrically shaped. The wave, of course, may be varied considerably, and if desired may be of the saw-tooth form having one edge of each tooth inclined and the other edge thereof substantially vertical.

Various types of clipper gates may be employed at 44, the example shown being of a type having two dry rectifiers 47 and 48. The two rectifiers are connected back to back and a small positive voltage is applied over resistor 49 to the inter-

mediate point 50. The resistor 49 is preferably at least several times larger than the low "forward" resistance of the rectifiers, although it should be low in comparison with the high "back" resistance thereof. The input wave 46, graph *p* is applied through coupling condenser 51 to resistor 52 which is preferably several times smaller than resistor 49. The output of the circuit is delivered across resistor 53 which may be of the same order of magnitude as resistor 52.

For modulating the clipping action the amplitude modulated pulses such as 39, 40, 41, etc., of channel 1 are applied through resistor 52 to rectifier 47. The relationship between clipping levels 47a, 48a of the clipper gate and wave 46 shown in alignment with the pulses of the fourth channel, graphs *m* and *p*, Fig. 5, represents the condition when the amplitude modulated pulse input is of an amplitude corresponding to the maximum negative value of the signal energy for such channel. The action of the two rectifiers is that of limiting the passage of input wave 46 between levels 47a and 48a. The application of energy to the circuit through resistor 52 operates to vary the location of these two levels relative to the amplitude of the wave 46.

This double limit clipping results in a rectangular or trapezoidal wave form such as indicated in graph *q*. This rectangular wave is applied to a differentiator 54 which converts each rectangular pulse portion of the wave into alternately positive and negative pulses as indicated by graph *r*. It will be noted that the rectangular pulse portion 55 corresponding to the clipping of wave 46 in alignment with channel 4 produces a narrow pulse which, when generated, produces positive and negative pulse 55a and 55b. The amplitude modulated pulse 39 of channel 1 shifts the clipping levels of gate 44 to a lower portion 56 on wave 46. This produces a wider pulse 57 than the pulse 55. The increased width of pulse 57 over pulse 55 corresponds to the increased signal value represented by the amplitude of pulse 39. Accordingly, the pulses 57a and 57b are separated by a time interval corresponding to the width of pulse 57. Likewise pulses 58a and 58b resulting from pulse 58 are displaced a greater time interval corresponding to the greater amplitude of pulse 40, and the still greater pulse width 59 resulting from the clipping produced by pulse 41 produces pulses 59a and 59b having a corresponding greater time displacement. The pulses of graph *r* are applied to a threshold clipper circuit 60 by which pulses 55b, 57b, 58b, etc., are clipped at level 61. Of course, pulses 55a, 57a, 58a, etc., may instead be clipped whereby the time displacement of the output pulses will be in the opposite direction.

The output of the clipper 60 is applied to a mixer 62 to which is also applied synchronizing pulses 64 obtained by shaping the pulse output of pulse divider 35 at shaper 63. The synchronizing pulses 64 are shown in graph *s* to coincide with pulses 55b produced from the pulses of channel 4, and since the mixer 62 is preferably of the character having a limit clipping level 65, the synchronizing pulses 64 replace the pulses 55b. This results in a train of pulses indicated by graph *t* in which the synchronizing pulses 64 are of a width greater than the pulses of the channels 1, 2 and 3. This greater width of the synchronizing pulses makes it possible for the receiver to segregate the synchronizing pulses from the channel pulses by width discrimination

for use in deblocking circuits of the receiving channels.

For a more complete discussion of the time modulating principles of the clipper gate type of modulator and of variations thereof, reference may be had to the copending application of D. D. Grieg and myself, Serial No. 455,898, filed August 24, 1942.

From the foregoing description it is clear that I have disclosed a multi-channel communicating system requiring a single time modulator for a plurality of channels. Also, I have shown two different methods of producing the train of pulses to be time modulated and a second train of pulses, energy of which is used for each of the channels to obtain segments of the signal energy of the different channels. While I have indicated a base pulse producer from which these two trains are obtained it will be clear that in the place of a base pulse producer I may use a stable oscillator for producing a sinusoidal wave having the frequency desired for either train of pulses. By using a frequency multiplier or divider a wave of the frequency desired for the other pulse train may be obtained. The pulses may thereafter be produced from these two waves according to well known methods.

While I have shown and described particular embodiments of the present invention, it is recognized, of course, that many variations and different embodiments may be made without departing from my invention. It is therefore to be understood that this description is given by way of example only and not as a limitation on the scope of the invention as set forth in the objects thereof and the accompanying claims.

I claim:

1. A method of multi-channel transmission comprising producing a train of pulses, segregating spaced segments from the signal energies of a plurality of channels, differently timing the segments of the different channels to interleave them together into a series of segments wherein each segment corresponds to a pulse of said train, and time modulating the pulses of said train according to the amplitude of the corresponding signal segments.

2. A method of multi-channel transmission comprising producing a plurality of series of pulses differently timed so that the pulses of the different series interleave in time, producing a train of pulses corresponding to said plurality of series taken together, translating the pulses of each series into signal pulses the amplitude of which vary according to the instantaneous values of the signal energy of a corresponding channel, and time modulating the pulses of said train according to the amplitude of the corresponding signal pulses.

3. A method of multi-channel transmission comprising producing a train of pulses of a given repetition frequency, dividing the pulse energy of said train to obtain a series of pulses of a lower repetition rate such as may be desired for channel communication, retarding by different amounts the energy of said series of pulses to obtain a plurality of series of pulses of different timing so that they interleave in time similarly as the pulses of said train, translating the pulses of each series into signal pulses the amplitudes of which vary according to the instantaneous values of the signal energy of the corresponding channel, and time modulating the pulses of said train according to the amplitude of the corresponding signal pulses.

4. A method of multi-channel transmission comprising producing a series a pulses of a repetition rate desired for channel communication, multiplying the pulse energy of said series to obtain a train of pulses having a repetition frequency corresponding to a given plurality of channels, retarding by different amounts the energy of said series of pulses to obtain a plurality of series of pulses of different timing so that they interleave in time similarly as the pulses of said train, translating the pulses of each series into signal pulses the amplitude of which vary according to the instantaneous values of the signal energy of a corresponding channel, and time modulating the pulses of said train according to the amplitude of the corresponding signal pulses produced from said plurality of series.

5. A method of time modulating pulses comprising producing a first train of pulses varying in amplitude according to the instantaneous values of a given signal energy, producing a second train of pulses having a repetition frequency corresponding to the repetition frequency of the amplitude modulated pulses, and time modulating the pulses of said second train according to the amplitude values of the corresponding pulses of said first train.

6. A system for time modulating pulses comprising means for producing a train of signal pulses of a given repetition frequency, the pulses of which vary in amplitude according to instantaneous values of a given signal wave, means for producing a second train of pulses having said repetition frequency, and means for varying the time positions of the pulses of said train in accordance with the amplitude values of the corresponding signal pulses.

7. A multi-channel transmission system comprising means for producing the plurality of series of pulses differently timed so that the pulses of said plurality of series interleave in time, means for producing a train of pulses corresponding to said plurality of series taken together, means for translating the pulses of each series into signal pulses the amplitudes of which vary according to the instantaneous values of the signal energy of a corresponding channel, and means for time modulating the pulses of said train according to the amplitude of the corresponding signal pulses.

8. A system according to claim 7 wherein the means for translating the pulses of each series into signal pulses includes a normally blocked amplifier for the signal energy of each channel and means to apply one of said series of pulses to unblock each said amplifier for the duration of each pulse of such series.

9. A system according to claim 7 wherein the means for time modulating the pulses of said train includes delay means for retarding the time

position of the pulses and means for applying the signal pulses of varying amplitude to said delay means to vary the retardation effect thereof on the pulses of said train.

10. A system according to claim 7 wherein the means for time modulating the pulses of said train includes means for producing a zig-zag shaped wave from said train thereby providing triangularly shaped undulation having at least one inclined edge to correspond to each pulse of said train, means for gate clipping the undulations between two levels, means for varying the clipping levels of the gate clipping means relative to the amplitude of each undulation according to the amplitude of the corresponding signal pulse, and means for differentiating the clipped portions of the undulations to obtain pulses, the time positions of which represent the time position of the clipped portion of the corresponding inclined edges of said undulations.

11. A multi-channel transmission system comprising means for producing a first train of pulses, means for producing a second train of pulses the repetition frequency of which is a multiple of the repetition frequency of said first train of pulses, retardation means for retarding the pulse energy of said first train of pulses to produce a plurality of series of pulses differently timed so that the pulses taken together correspond to the pulses of said second train, separate means for varying the amplitude of the pulses of each series according to the instantaneous values of the signal wave of a corresponding channel, and means to time modulate the pulses of said second train according to the amplitude values of the pulses of said plurality of series.

12. A system according to claim 11 wherein the means for producing the pulses of the second train includes means for multiplying the pulses of said first train.

13. A system according to claim 11 wherein the means for producing the pulses of said first train includes means for dividing the pulses of said second train.

14. A system according to claim 11 wherein the means for varying the amplitude of the pulses of each series includes a normally blocked amplifier for the signal energy of each channel and means to apply one of said series of pulses to unblock each said amplifier for the duration of each pulse of such series.

15. A system according to claim 11 further including means to produce a synchronizing pulse channel comprising means for mixing the pulses of said first train with the time modulated pulses of said second train, the pulses of said first train being distinguished in width from said time modulated pulses.

EMILE LABIN.
